SOUND RECORDING AND REPRODUCING
MECHANISM

Chester W. Larner, Philadelphia, Pa.

Application January 5, 1934, Serial No. 705,314

20 Claims. (Cl. 74—424.5)

In the art of sound recording and reproducing mechanism, one of the most important problems has been that of increasing the capacity and playing time of disc records. In this respect the only improvement which has been adopted commercially has been accomplished by reducing the R. P. M. of the records. This necessitates reducing the minimum speed of the needle in the groove of the record and it is impossible to accomplish much in this way without resulting in a deterioration in the quality of reproduction.

The minimum speed of travel of the needle in the groove is the determining factor in this problem and it is obvious that, if the record is rotated at constant R. P. M., the speed of the needle in the groove will be at all times higher than necessary until the needle has reached the final and innermost groove, assuming that the needle starts in the outermost groove, as is usual.

Hence it is clear that the capacity of a record can be increased to a maximum only by arranging a variable speed drive such as to effect a constant speed of the needle in the groove, this speed being the minimum which will give a reproduction of satisfactory quality. A 12" record operating at constant needle speed will play about twice as long as at constant R. P. M.

However, all records so far produced have been of the constant R. P. M. type and there are immense quantities of these records in the hands of the public so that any type of reproducing machine to be generally accepted must be capable of playing the existing constant R. P. M. records as well as constant needle speed records.

One object of my invention is to provide a compact and dependable mechanism for recording and reproducing disc sound records at a constant speed of the needle in the groove.

Another object of my invention is to provide a mechanism capable of recording and reproducing disc sound records at a constant needle speed and also at a constant R. P. M.

Another object is to provide a mechanism of the type aforesaid which is adaptable to two series of records of the constant R. P. M. type operable at two different speeds.

Another object is to provide various alternative methods of operating the aforesaid mechanisms.

Fig. 1 is a cross-sectional elevation of a sound recording and reproducing mechanism utilizing a spiral gear of the disc type.

Fig. 2 is a view in elevation of the mechanism of Fig. 1 showing mechanism for shifting the driving pinion.

Fig. 3 is a fragmentary cross-sectional side view of Fig. 2.

Fig. 4 is a view in elevation of an alternate arrangement of the mechanism shown in Fig. 2.

Fig. 5 is a fragmentary cross-sectional side view of Fig. 4.

Fig. 6 shows three views of the driving pinion and shifting block of Fig. 1.

Fig. 7 is a cross-sectional elevation of a sound recording and reproducing mechanism utilizing a spiral gear of the conical worm type.

Fig. 8 is a cross-sectional plan of Fig. 7 taken substantially on the line 8—8 showing the worm track as if it were circular instead of spiral in order to simplify the drawings.

Fig. 9 is a cross-sectional elevation of a sound recording and reproducing mechanism utilizing a spiral gear of the conical spur gear type.

Fig. 10 is a cross-sectional plan of Fig. 9 on the line 10—10 with the spiral gear omitted.

Fig. 11 is a cross-sectional elevation of a modification of Fig. 1 showing a method of automatically resetting the spiral gear to the proper starting position.

Fig. 12 shows a modification of the resetting cams or nuts of Fig. 11.

Fig. 13 is a cross-section on line 13—13 of Fig. 11 and shows a modified detail of the resetting cams or nuts.

Fig. 14 is a diagrammatic representation of the spiral gear track used in Fig. 1.

Fig. 15 shows a modification of Fig. 14.

Fig. 16 shows radial and circumferential cross-sections through the spiral gear track of Fig. 14.

Fig. 17 shows a cross-section in elevation of an arrangement similar to Fig. 1 illustrating a method of using a spiral gear track in combination with two circular gear tracks for playing two sets of constant R. P. M. records recorded at different speeds. It also shows an alternative method of playing the two sets of constant R. P. M. records by means of a gear shift and an electrical means of resetting the spiral gear at the proper starting point.

Fig. 18 shows the electrical circuit for controlling a motor drive in combination with the electrical resetting means of Fig. 17.

Fig. 1 shows one form of my invention. The mechanism is contained in a circular housing fitting into the top board 2 of the case in which it is mounted. The housing 1 has radial ribs 3 which support the bearings 4 and 5 for the shaft 6 which drives the turntable 7 which carries the record 8.

The disc 9 is rotatably mounted on shaft 6 and 55

runs on the rollers 10 of which three or more are provided, supported by the ribs 3 or in any other convenient manner. A spiral rack or groove provided with gear teeth 11 is cut or impressed in the lower face of 9 and these teeth mesh with a gear pinion 12 on the shaft 13. Shaft 13 is driven by a worm wheel 14 which is in turn driven by a worm 15. Worm 15 is driven directly or through intermediate gearing by a constant speed electric motor as is customary in the art. Disc 9 has a cover 16 provided with a knob 17 located opposite the beginning of the outer groove of the spiral track. Knob 18 is in line with the axis of pinion 12 and when knobs 17 and 18 are together, or approximately so, the spiral gear track is in proper position to begin playing a record.

The outer circumference of disc 9 is provided with gear teeth meshing with pinion 19 driving countershaft 20 which, by means of sprocket 21, chain 22 and sprocket 23, drives shaft 6 and turntable 7. The proper gear ratio between disc 9 and turntable 7 depends upon the size of 9 relative to 7 and the ratio between the radial pitch of the spiral gear and that of the grooves on the record. In Fig. 1, A, B, C and D are the radial distances, respectively, of the outermost groove on the record, the innermost groove on the record, the pitch line of the outermost spiral gear track and the pitch line of the innermost gear track and if $A=C$ and $B=D$, then the gear ratio equals the pitch ratio. In other words, if the pitch of the grooves on the record is 0.01" and the pitch of the spiral gear is 0.25", then the gear ratio is 25:1. Fig. 17 illustrates the case where $A=C$ and $B=D$.

In order to effect a constant speed of the needle in the groove, the relation $A:C=B:D$ must be maintained but if A is not equal to C the gear ratio is no longer equal to the pitch ratio. This is the case in Fig. 1.

Suppose $C=0.8A$. Then the gear ratio must be

$$\frac{25}{0.8} : 1 = 31.25 : 1$$

If the gear pitch is also reduced proportionately so that the number of gear tracks is unchanged, the gear ratio will remain unchanged.

The spiral gear track and the groove on the record are both true spirals and hence if the relation $A:C=B:D$ is maintained so that the pinion 12 will be at radius D when the needle reaches radius B, it follows that travel of the needle in the groove will have the same characteristics as the travel of the pinion 12 in the spiral gear. Pinion 12, being driven by a constant speed motor, rolls around the spiral gear track at constant speed and therefore the needle travels at constant speed in the groove of the record.

The general relations, mathematically expressed, are as follows:

Assuming $A:C=B:D$

Let m =radial pitch of needle groove on record.
 n =radial pitch of spiral gear track.

t =linear speed of needle in groove.

v =peripheral speed of pitch circle of pinion 12.

Then

$$\frac{n}{m} \times \frac{A}{C} = \frac{t}{v}$$

In connection with the several disclosures of this invention, it is necessary to consider at least three types of disc records, hereinafter referred to as X, Y and Z.

Type X is the 78 R. P. M. record which has been made for many years. This record has a mini-

mum needle speed of about 1000 inches per minute.

Type Y is the more recent 33 1/3 R. P. M. record which has a minimum needle speed of about 500 inches per minute.

Type Z is a proposed type of record to be made at a constant needle speed which would be the minimum needle speed suitable for good sound reproduction. Under present conditions this would probably be the same as for Type Y, 10 namely, about 500 inches per minute.

To play a Z record on the mechanism of Fig. 1 the pinion 12 is set in the position shown by means hereafter described. The driving motor is started and the needle set in the outer groove of 15 the record. The pinion 12 is slidably mounted on shaft 13 and driven by key 24. As it rotates, the pinion is fed toward the center of disc 9 by the spiral groove 11 into which it is meshed and it is assisted by the spring 25 acting upon the lever 26 20 which engages the pinion by means of a forked end provided with pins which fit into grooves 27 on each side of a square collar 28 which is rotatably associated with pinion 12 as shown in Fig. 6. It will be noted that one face of pinion 12 has a 25 convex form to fit the concave outer periphery of the spiral track in which it runs. As already explained, the rotation of pinion 12 in spiral track 11 rotates the record 8 at a uniformly accelerated speed and maintains a constant speed of the 30 needle in the groove.

The spiral track 11 terminates at radius D in a circular track 29, which serves two purposes. It prevents pinion 12 from running out of the spiral groove if the motor should fail to stop after play- 35 ing a record and it provides a means of driving the turntable at a constant R. P. M. for records such as Y. Such records would be recorded at a speed of rotation which would give a minimum needle speed approximately the same as the con- 40 stant needle speed used for Type Z records. Thus the position of circular track 29 would naturally coincide with the inner end of track 11.

This arrangement is better illustrated in Fig. 14, wherein the heavy lines and blackened areas in- 45 dicate partitions separating the gear tracks. This figure is diagrammatic and shows the gear track viewed from below.

The partition between 11 and 29 gradually tapers until it ends at 30. The space 31 is common to both 11 and 29 and is long enough to permit pinion 12 to shift from 11 to 29 as a result of the tension of spring 25. This change therefore occurs automatically and pinion 12 will continue to run in track 29 until it is manually 55 shifted. Line 32-32 is the starting position of the gear and track 11 is carried past 32-32 to 33 so that it is unnecessary to set the gear with ac- 60 curacy for starting.

The pitch of the teeth in track 11 increases 60 somewhat when it runs into the space 31 because this pitch is the radial projection of the pitch of track 29 which is the same as the pitch of 11. The teeth of pinion 12 must be loose enough to allow for this. There is a slight acceleration of 65 speed of the needle in the groove when pinion 12 passes point 30. It is advisable to complete the recording before this point is reached so that the needle will be running in a blank groove.

Fig. 16 shows radial and circumferential frag- 70 mentary cross-sections through the gear tracks 11 of disc 9 and illustrates a method of providing cut gear teeth, if desired. The proper width of the partition 34 is determined and a spiral groove of rectangular cross-section and having width equal 75

to the radial pitch minus the thickness of the partition, is machined in the face of disc 9. A gear rack 35 is then made in sections of convenient length to fit into the spiral groove and it is bent into spiral form and fastened in place at suitable intervals by rivets 36. The teeth of rack 35 and pinion 12 should be sufficiently rounded or pointed so they will fall into mesh readily and the partition 34 should extend somewhat beyond the rack 35 so that the pinion 12 cannot move radially even though it fails to mesh with rack 35. It will then be in position to mesh as soon as pinion 12 starts to turn.

To reset pinion 12 for playing another Z record, the first operation is to push down button 37 on rod 38, depressing one end of lever 39 which is pivoted in a bearing 40 mounted on the bottom 41 of the phonograph case. This lifts the pivot bearing 42 which in turn lifts shaft 6 and disc 9 sufficiently to clear pinion 12. Then, while holding down button 37 with one hand, the resetting lever which operates lever 26 is thrown over with the other hand, shifting pinion 12 to the starting position as shown in Fig. 1. Button 37 is then released, dropping disc 9 and locking pinion 12 in position shown in Fig. 1.

The mechanism which operates lever 26 is shown in Figs. 2, 3, 4 and 5. The rocker shaft 43 carried in bearings 44 and keyed to lever 26 is also keyed to a lever 45 which is connected by rod 46 to lever 47. Lever 47 is keyed to rocker shafts 48 (Figs. 2 and 3) which is in turn keyed to lever 49. When lever 49 is thrown to the left, pinion 12 is set at the starting point; when thrown to the right pinion 12 goes to the position shown in broken lines, Fig. 1. This is the position for playing Y records.

Lever 49 swings automatically from left to right during the playing of a Z record. It also swings automatically from left to right whenever button 37 is pressed down because, whenever pinion 12 is released by the lifting of disc 9, the tension of spring 25 throws it over.

Obviously to set pinion 12 to play a Y record it is necessary merely to press down button 37 and release it. After playing a Y record no resetting is necessary to play another Y record.

In resetting to play Z records, it is also necessary to turn disc 9 until knobs 17 and 18 are opposite, or approximately so. This brings pinion 12 into mesh with the beginning of the spiral groove 11 when the needle starts to traverse the groove of the record. Various means of resetting disc 9 are disclosed herein. These means are variously applicable to the several alternative designs of driving mechanism illustrated herein and it is, therefore, believed advisable to defer description of the resetting means until after description of the driving mechanism has been completed.

Figs. 4 and 5 show a design of shifting lever which dispenses with button 37. Rocker shaft 50 has a block 51 on one end which is bored for lever 52 so that 52 may slip up and down in it and when 52 is thrown one way or the other, shaft 50 is rotated. On the end of 52 is a cam 53 which engages a cam 54 on the end of a pin 55. When 52 is pushed down through 51, 53 pushes against 54, pushing 55 down against the end of lever 39 and raising disc 9. This unlocks pinion 12 and lever 52 may be thrown to a new position. The lower face of cam 53 is shaped to conform to a radius struck from the center of shaft 50 when the cam is depressed to the lower position indicated in dotted lines. In this way, after lever 52 has been pushed down, the cam 53

has no further effect on cam 54 when lever 52 is swung from one position to another.

An alternative shifting arrangement is shown in broken lines in Fig. 2 where the lever 56 is keyed to a prolongation of shaft 43, bringing lever 56 into the same plane in which lever 49 is shown by Fig. 3.

Figs. 7 and 8 show another embodiment of my invention which utilizes a different form of spiral gear. The cylindrical housing 57 has radial ribs 10 58 which support bearing 59 and two generally circular parallel flanges 60 and 61, both of which are provided with projections 62 to guide the worm bearings 63. The latter are of rectangular cross-section, made in halves to permit introduction of the worm shaft 64 and finished to fit slidably between flanges 60 and 61.

Shaft 65 which drives turntable 1 is itself driven by sprocket 66, chain 67, sprocket 68, countershaft 69, pinion 70 and gear 71. Gear 71 rotates in bearing 72 which is connected to flange 73 by ribs 74. Flanges 61 and 73 are rigidly connected together. Shaft 65 rotates freely in a tubular shaft 75 which is keyed to gear 71. Sprocket 66 is non-slidably mounted on shaft 65 25 and the weight of both shafts and connected parts is carried on pivot bearing 76.

The spiral gear 77 is of conical form having worm teeth 78 cut around its periphery in a spiral track which terminates at the small end of the cone in circular track 79. The track is cut by a cutter, having the same form as the worm 80, which is held in the same position relative to the cone as the worm and is fed axially of the cone at the proper rate while the cone is rotated at the proper rate. The track is cut to the depth of the radius of the worm so that, when the worm is engaged, it locks 77 against axial movement.

Gear track 79 is used for playing Y records and 78 is used for Z records. The gear ratios 40 are determined according to the principles explained in connection with Fig. 1.

Spiral gear 77 is keyed to shaft 75 so as to permit axial movement of 77. Worm 80, which rotates in bearings 63, is driven by shaft 64. 45 Shaft 64 is connected to the shaft of worm-wheel 14 by a universal joint 95 so that shaft 64 and worm 80 can swing in a horizontal plane. Worm 80 is driven at constant R. P. M. and hence the peripheral speed of the spiral gear 50 which it engages is constant. Bearings 63 are connected by a T-frame 81 which extends through an opening in 57 and engages with a lever which pivots at a bearing 83 and extends upward through an opening in 2 so that it may be manually operated, the same as lever 49 of Fig. 2. When lever 82 is swung on the pivot 83, lever 81 swings with it, thus causing worm 80 to approach or recede from the spiral gear track. Spring 84 holds the worm in engagement with the 60 gear when not under control of lever 82.

To play Z records, the worm is set in the gear track at the large end of the cone. The motor is started and gear 77 is rotated. Inasmuch as worm 80 is held against vertical movement, gear 65 77 slips down shaft 75, being assisted by spring 85, until the worm reaches track 79, turntable 1 being meanwhile driven at a speed to maintain a constant rate of travel of the needle in the groove of the record. When the worm is in track 79, 70 the turntable is running at constant R. P. M., suitable for playing Y records. Gear 77 drives gear 71 by means of key 86 in shaft 75, which is common to both.

To reset the spiral gear for playing Z records, 75

lever 82 is thrown to the left thus withdrawing worm 80 radially to a distance sufficient to clear the largest diameter of gear 77. Button 87 is then pressed down, shifting gear 77 to the position where worm 80 is opposite the beginning of the spiral track at the large end of 77. This is the position shown in Fig. 7. Lever 82 is then released and spring 84 throws worm 80 into engagement with gear 77 and locks 77 against vertical movement so that button 87 may be released. Button 87 operates to shift gear 77 through rod 88, lever 89 and block 90 which is rotatably but not axially movable on gear 77. Lever 89 is made of two spaced bars to straddle shaft 69. It works on a fulcrum 91 which is supported from housing 57. It is connected at one end to rod 88 and spring 85, and at the other end it has a yoke 92 which straddles block 90 and is connected to it by pins 93 which slide in grooves 94. By this means lever 89 is capable of raising and lowering gear 77, at the same time leaving it free to rotate.

To reset the gearing to play Y records it is only necessary to throw lever 82 to the left and then release it. The tension of spring 85 will automatically shift gear 77 so that the worm 80 will fall into engagement with track 79. To continue playing Y records no resetting is necessary.

Figs. 9 and 10 show another embodiment of my invention which utilizes a spiral gear of conical form which engages a spur gear instead of a worm, as illustrated in Figs. 7 and 8. In this case the spiral gear has no vertical movement, the shift being accomplished by two motions of the driving pinion, one vertical by depressing a button and the other radial by swinging a lever.

The housing 95 has ribs 96 and 96' which support bearing 97. Bearing 97 contains the lower end of shaft 98 which drives turntable 7. The weight of shaft 98 and connected parts is carried on pivot 99. Shaft 98 is driven by sprocket 100, chain 101, sprocket 102, countershaft 103 and pinion 104. Pinion 104 is driven by gear 105 which is keyed to a tubular shaft 106 which revolves on shaft 98 and guides the upper end of 98. Gear 105 runs on three or more rollers 10 which are supported from the housing 95 in any suitable way. These rollers maintain gear 105 in proper alignment.

Spiral gear 108 abuts against gear 105 and drives it by means of key 107 which is common to both. Gear 108 is of conical form having a spiral gear on its periphery as shown. This gear may be formed by cutting spiral steps in the surface of the cone and wrapping a gear rack around the steps, fastened in place by rivets or other suitable means. In that case the teeth 109 make a slight angle with the teeth of the driving pinion 110 but the latter are made sufficiently loose so that this discrepancy is immaterial. The spiral track 109 ends in a circular track 111 which is used for playing Y records.

The relations governing ratios of gearing between 108 and 7, which were explained in connection with Fig. 1, apply in this case also.

Pinion 110 is driven by shaft 112 through a pair of bevel gears 113 and 114. Shaft 112 is driven by shaft 115 through a pair of bevel gears 116 and 117. Swinging arm 118, having brackets and bearings at each end, supports pinion 110, bevel gears 113, 114, 116 and 117, and shaft 112 in proper relation to each other. Arm 118 swings freely on shaft 115, permitting pinion 110 to approach or recede from gear 108 in a radial di-

rection. This motion is accomplished by means of a projecting lug 119 on arm 118. Lug 119 passes through a slot in lever 120 so that, when lever 120 is swung on its pivot 221, arm 118 swings as indicated in Fig. 10. Spring 121, connecting arm 118 to the opposite side of housing 95, holds pinion 110 in engagement with the gear track on gear 108 except when it is displaced by swinging lever 120.

Arm 118 is also slidable vertically on shaft 115 to permit pinion 110 to work up and down on gear 108. Bevel gear 117 has a key in its bore which slides in the keyway 122 so that 117 is driven by shaft 115 in all positions. Shaft 115 is driven at constant speed by a constant speed 15 motor through worm shaft 15 and worm wheel 14. The lower end of bearing 123 on the end of arm 118 is provided with a shifting block 124, similar in design to 28 of Fig. 6, which engages pins 125 in the forked end of lever 126, which thus serves to raise and lower arm 118. Arm 118 is automatically urged upward by the tension of spring 127 acting on lever 126. In order to lower arm 118, button 128 on rod 129 is pressed down. Rod 129 is connected to lever 130 which engages 25 one end of lever 126. The fulcrum 131 of lever 126 is supported by rib 96' and the fulcrum 132 of lever 130 is supported by bearings 133.

To play Z records, lever 120 is swung in the proper direction to release pinion 110 from engagement with gear 108. Spring 127 then acts upon lever 126 to raise arm 118 until bearing 134 strikes against bearing 135. This brings pinion 110 opposite the beginning of the gear track on 108. Lever 120 is then released and spring 121 35 brings pinion 110 into engagement with gear 108. The motor is then started and pinion 110 rotates 108, being fed downward by the spiral shoulder 136 until it runs onto the circular track 111. When it is in track 111 it is set to play Y 40 records.

If the pinion is in any position above track 111 and it is desired to play Y records, button 128 is pressed down and inward against spring 137 until collar 138 latches under lug 139. This sets 45 pinion 110 in track 111 and holds it there. To reset for playing Z records after playing Y records collar 138 must be unlatched, otherwise spring 127 will be ineffective.

In respect to all three arrangements shown in 50 Figs. 1, 7 and 9, it will be noted that the housing containing most of the mechanism can be withdrawn through the opening in the top of the case by disconnecting only a few parts. This is a great convenience in case of repairs.

Also in each case the working parts are readily accessible for lubrication, cleaning and adjustment. The turntable 7 can be removed in each case by unscrewing cap 136 which centers the record. In Fig. 1, the dustcover 16 with gear 9 60 attached can then be slipped off shaft 6 and removed. This leaves practically all of the mechanism exposed. Similarly, in Fig. 7, dustcover 16 with gear 71 attached may be removed and, in Fig. 9, dustcover 16 with gear 105 attached may be removed.

In the foregoing description of the spiral gears, methods have been described for providing machine finished teeth. This is not necessary except in the case of Fig. 7. In Figs. 1 and 9 the 70 gears can be made by various well known methods for accurate casting or die stamping in a variety of materials. Extreme accuracy is unnecessary inasmuch as the teeth must fit loosely with the driving pinion. If light materials are 75

used, it may be necessary to add weight to the dustcover 16 in the cases of Figs. 1 and 9 to hold the gears properly meshed. This is particularly true of Fig. 1 when pinion 12 tends to lift gear 9.

5 In none of the figures has any attempt been made to show the connections to the motor because they would vary with the speed of the motor and its location. These connections are familiar to those informed in the art.

10 Also various combinations of gearing may be utilized to connect the spiral gear to the turntable shaft, provided the combination effects the proper gear ratio. Thus, for example, the sprockets might be replaced with spur gears and 15 an idler gear placed between them, in this way dispensing with the chain.

In the recording and playing of Z records, it is not necessary to start the needle at the outer edge of the record and feed it toward the center. 20 In Fig. 1, for example, the needle may start at radius B and stop at radius A, or thereabouts, depending on the length of the record. In that event, however, the pinion 12 must move in the same direction, starting at radius D and moving 25 toward radius C. This would, of course, necessitate some changes in the shifting mechanism. Spring 25 would have to act in the opposite direction in order to start pinion 12 out of the circular track 29 and into the spiral track 11. Also it 30 would be necessary to provide a means of locking pinion 12 in track 29 for playing Y records. Various means of accomplishing these results will be obvious to those skilled in the art.

35 *Resetting the spiral gear.*—In recording and reproducing Z records, it is desirable that the driving gear or pinion should be started at the beginning of the spiral gear track, or approximately so. If a record is made in this way and, when being played, the gear is started at some 40 other point in the spiral track, the speed of the needle in the groove will not be the same as the speed at which it was recorded. Some deviation in this respect is permissible without affecting the quality of reproduction but not very 45 much.

In all of the arrangements shown, the stationary knob 18 and the knob 17, which rotates with the spiral gear, are so located that, when they are in juxtaposition, the driving gear or pinion 50 is set to enter or mesh at or near the beginning of the spiral gear track. This starts the spiral gear and the needle in the proper relation to each other. However, the playing length of records differs and therefore it is impossible to arrange 55 to have knob 17 stop opposite knob 18 when the driving motor is stopped at the end of the record. It is therefore necessary, when preparing to play a Z record, to reset the spiral gear so that knobs 17 and 18 are opposite, or approximately so. Precision in this respect is unnecessary. For example, if playing 12" records with $A=C$ and knob 17 should be 3 inches away from knob 18, the result would be that the spiral gear would be about $\frac{1}{2}$ of a revolution away from 60 its correct position. Assuming a gear ratio of 25:1 this would mean that the record would have made about 2 revolutions while the knob 17 was moving 3 inches beyond knob 18 and therefore if the needle is started in the outer 65 groove of the record when 17 is 3 inches beyond 18, the needle will be two grooves farther from the center of the record than it should be. This discrepancy would have no appreciable effect on the quality of sound reproduction. To play constant 70 R. P. M. records X and Y the driving gear

or pinion is not using the spiral track and hence with them no resetting of the spiral gear is necessary. It is necessary only with Z records.

The spiral gear of Figs. 1, 7 and 9 may be reset by hand. Pinions 19, 70 and 104 are not keyed to the countershaft. The latter is driven by a so-called "free-wheeling clutch" 140 of well known construction which permits the pinion to turn freely in the reverse direction. It is therefore possible to turn the spiral gear backward 10 by hand until knobs 17 and 18 are opposite. This is, of course, done with the spiral gear disengaged from the gear which drives it.

Another method of resetting is illustrated diagrammatically in Fig. 15 where the heavy lines 15 and blackened areas represent partitions separating the gear tracks of a spiral gear similar to 9 of Fig. 1. In Fig. 15 a circular track 141 is added surrounding the spiral track 11 with a partition 142 between them. Partition 142 is cut 20 away at the beginning of spiral track 11 sufficiently to allow pinion 12 to shift from track 141 to track 11 as soon as it reaches the opening 143. This is effected by the tension of spring 25.

When starting to play a Z record, pinion 12 is 25 meshed in track 141 and the driving motor started but the needle is not applied to the record until knobs 17 and 18 are opposite. Knob 17 is opposite the center of space 143 and hence the position of the needle on the record and the 30 position of pinion 12 in spiral groove 11 have the proper relationship.

Fig. 11 shows a means of resetting the spiral gear automatically during the operation of lifting it preparatory to resetting pinion 12. The shaft 35 144, which drives turntable 7, passes through a tubular shaft 145 which is keyed to spiral gear 9 and rotates with it. A collar or nut 146 having a helical face 147 is fixed on shaft 145. The helix has a steep pitch and makes one revolution, 40 beginning and ending at the vertical face 148 which projects radially from shaft 145. Nut 146 turns with spiral gear 9. A similar nut 149, having a vertical face 150 and helical face 151, complementary to 147 and 148 of nut 146, is 45 slidably mounted on shaft 145 but is held from turning by the double lever 152 which is used to raise and lower it. The vertical faces 148 and 150 are in alignment when knobs 17 and 18 are 50 together.

To reset the spiral gear with this mechanism, button 37 is pushed down lifting nut 149 by means of rod 153 provided with a pin 154 which engages levers 152 which are slidably fulcrumed by a bridge 155 supported between ribs 156. 55 When face 151 of nut 149 engages face 147 of nut 146, the first effect is to lift nut 146 which in turn lifts shaft 145 and spiral gear 9 until the top of nut 146 engages the bottom of bearing 157. This disengages pinion 12 from the spiral 60 gear track. The helical faces 147 and 151, if well lubricated, then have a tendency to turn on each other but, since nut 149 cannot turn, all of the motion is imparted to nut 146 which turns until face 148 comes against 150. Spiral 65 gear 9 turns with nut 146, the helix being so formed as to produce rotation of 9 in the reverse direction so that clutch 140 does not drive countershaft 20, as previously explained. After 148 and 150 come together, rotation is, of course, 70 checked and knobs 17 and 18 are together. Button 37 is then released and spring 151 returns nut 149 to the position shown in Fig. 11, spiral gear 9 dropping into mesh with pinion 12.

Fig. 12 shows an alternative arrangement of 75

the two nuts wherein a wheel 158 is used, projecting slightly below the helical surface of nut 146'. This wheel rides around the helix of nut 149', preventing the two surfaces from touching and reducing the frictional resistance materially. It is desirable to minimize friction because otherwise the pitch of the helix must be very steep which makes the nuts long and increases the vertical space occupied by the mechanism. The 10 friction is greatest when the two helixes lap only slightly as would be the case in Fig. 11 if the face 148 were turned slightly to the left from the position shown. To overcome this difficulty a spring 159 is attached to one of the ribs 156 so 15 as to be deflected by a pin 160 in nut 146 as the latter passes the position shown in Fig. 11. If nut 146 stops while still engaged with spring 159, the latter will start nut 146 rotating in the reverse direction when button 37 is depressed and 20 the pitch of the helix will continue the motion.

Figs. 17 and 18 show a method of resetting the spiral gear by means of the electric motor drive. A slip ring 160 with two contact brushes 161 and 25 162 is attached to dust cover 163 with insulation 164 as shown. Slip ring 160 is provided with an insert of insulating material 165 which breaks the circuit through the ring when it covers brush 161.

Fig. 18 shows a diagram of the electrical circuits for controlling the mechanism of Fig. 17. The motor 166 which drives shaft 15 (Figs. 1, 20 7, 8, 9 and 10) is connected to the source of current through two circuits, one controlled by the switch 167 and the other controlled by the 25 slip ring 160. Switch 167 is the usual form of starting switch and is located adjacent the record turntable so that, when the needle reaches the last groove on the record, the needle arm opens switch 167. Opening switch 167, however, 30 does not stop the motor since current continues to flow through the slip ring until the insulated gap 165 blanks brush 161. The motor then stops. Line S—S passes through knobs 17 and 18 and 35 locates the proper starting position of the spiral gear. Insulation 165 and brush 161 should be so placed in respect to each other that, allowing for the over-run 168 after current is cut off from the motor, the line S—S will pass through both knobs 17 and 18, or approximately so. This 40 leaves the spiral gear set in the proper position for playing a new record.

It is clear that, whether switch 167 be opened by the needle arm at the conclusion of a record or by hand during the playing of a record, the 45 spiral gear will continue to rotate until it comes to its proper starting position. It is equally clear that the contact of insulation 165 with brush 161 will not stop the motor as long as switch 167 is closed, as it is during the playing of a record.

It is undesirable that the record should 50 continue to revolve after the needle reaches the last groove and while the spiral gear is turning around to its starting position because this would cause an unpleasant scratching sound. It is, 55 therefore, desirable to use the customary friction brake acting on turntable 7 which is set by the needle arm at the same time it opens switch 167. The use of this brake is made possible by mounting pinion 169 rotatably on countershaft 170 and 60 driving the latter by means of a friction clutch so adjusted that it is tight enough to drive turntable 7 when there is no resistance except the drag of the needle on the record but not tight enough to drive it when the brake is set by the 65 needle arm. Turntable 7 then stops at the end 70

of the record but the spiral gear continues to run until knobs 17 and 18 come together.

The friction clutch consists of a driving element 171 keyed to countershaft 170 and held against pinion 169 by a spring 172 which is adjusted by a cap 173 and nut 174.

The electrical apparatus of Fig. 18 is applicable to the mechanism of Figs. 1, 7 and 9, the friction clutch being substituted for the "free-wheeling" clutch in each case.

Mechanism for playing X, Y and Z records.—Fig. 17 shows two alternative methods of playing all three types of records with one mechanism.

In the first method, a spiral gear track 176 is provided in gear 175, extending from radius A to 15 radius B and ending in a circular track 180. Another circular track 177 is provided at radius E. Track 176 is used with Z records, track 180 with Y records and track 177 with X records. The mechanism for shifting pinion 12 must be modified to provide for setting the pinion in the three starting positions. Countershaft 170 drives shaft 179 as shown in Fig. 1.

The other method dispenses with track 177 and substitutes an additional chain drive for 25 179. The sprockets 276 and 181 are rotatably mounted on shaft 170 and are provided with clutch teeth which will mesh with the teeth on collar 183.

To play Y or Z records, lever 184 is thrown to 30 the position shown. Lever 185 takes the position shown, due to the pressure of spring 186, and block 183, which is driven by shaft 170 through a feather key, comes into engagement with sprocket 276, thus driving shaft 179 through chain 277 35 and sprocket 178. The gear ratio between sprockets 276 and 178 is suitable for Y and Z records.

To play X records, lever 184 is thrown to the right against stop 187, forcing block 183 down 40 into engagement with sprocket 181 and releasing sprocket 276. Shaft 170 then drives shaft 179 through sprocket 181, chain 182 and sprocket 178. The gear ratio between 181 and 178 is suitable for playing X records.

In both cases, the mechanism for resetting pinion 12 may be similar to that for Fig. 1 and the spiral gear may be reset by hand, by means of the outer circular groove or electrically, all these methods having been previously described.

In the foregoing description, it has been stated that the radius D is the radius of the end of the spiral gear track for playing Z records and also the radius of the circular gear track for playing Y records. This, of course, assumes that the spiral gear track continues in to that radius and merges with the circular track.

In practice that is impossible for two reasons as will be evident from Fig. 14. In the first place, after pinion 12 passes the end of partition 34 at 60 30, spring 25 pulls it into track 29. The blackened area 200 represents the continuation of the spiral track 11 which has been filled in by a solid 65 partition because it cannot be utilized.

Second, even if it were possible to hold pinion 65 12 in the spiral path for a complete turn from point 30 back to point 30, as, for example, by reversing the pull of spring 25, the effect would be the same as it is with the arrangement shown in 70 Fig. 14. This is due to the fact that from point 30 onward the teeth in the spiral track would have to be radial extensions of the teeth in the circular track and, therefore the rotative speed of gear 9 would be the same whether pinion 12 75

were working in the blackened area 200 or in track 29.

It is undesirable to utilize the track beyond point 30 for playing Z records on account of the speed change which occurs at this point, as previously explained. The best arrangement is to make the needle speed of Z records equal to the minimum needle speed of Y records and not record on the Z records beyond the point which 10 would correspond to point 30 on the spiral gear.

It will be obvious to those skilled in the art that various changes may be made in the apparatus herein described without departing from the spirit of the invention as set forth in the accompanying claims. No attempt has been made to show the needle used in connection with the disk records, the arm which holds the needle, the brake which stops the turntable or the mechanism by means of which the needle arm opens 20 the starting switch to stop the motor at the end of the record. All of these devices and apparatus are too well known in the art to require illustration or description.

I claim:—

25 1. In a mechanism for rotating a sound recording or reproducing disk, the combination of a turntable non-rotatably mounted on a shaft, a spiral gear rotatably mounted on said shaft, a constant-speed gear for driving said spiral gear, and gear mechanism whereby said spiral gear drives said shaft and rotates said turntable at a uniformly increasing or decreasing angular velocity.

2. In a mechanism for rotating a sound recording or reproducing disk, the combination of a turntable non-rotatably mounted on a shaft, a gear element rotatably mounted on said shaft and having a spiral gear track and a circular gear track, a constant-speed driving gear arranged to mesh alternatively in either of said gear tracks, and gear mechanism whereby said gear element drives said shaft and rotates said turntable at a constant angular velocity or at a uniformly increasing or decreasing angular velocity.

45 3. In a mechanism for rotating a sound recording or reproducing disk in contact with a needle, the combination of a turntable non-rotatably mounted on a shaft, a gear element rotatably mounted on said shaft and having a spiral gear track and a circular gear track, a constant-speed driving gear arranged to mesh alternatively in either of said gear tracks, and gear mechanism whereby said gear element drives said shaft and rotates said turntable at a constant angular velocity or at a variable angular velocity, said last named velocity being such as to maintain a constant linear velocity of the disk relative to the needle.

60 4. In a mechanism for rotating a sound recording or reproducing disk in contact with a needle, the combination of a turntable non-rotatably mounted on a shaft, a spiral gear rotatably mounted on said shaft, a constant-speed gear for driving said spiral gear, and gear mechanism whereby said spiral gear drives said shaft and rotates said turntable at a variable angular velocity such as to maintain a constant linear travel of the disk relative to the needle.

70 5. In a mechanism for rotating a sound recording or reproducing disk in contact with a needle, the combination of a turntable to support the disk, a constant-speed driving gear, gear mechanism for transmitting the movement of said driving gear to said turntable to rotate it at a con-

stant angular velocity, gear mechanism for transmitting the movement of said driving gear to said turntable to rotate it at a variable angular velocity such as to maintain a constant linear travel of the disk relative to the needle, and 5 selective means for causing either of said gear mechanisms to become operative.

6. The combination of claim 5 further characterized in that the second named gear mechanism includes a spiral gear.

10 7. The combination of claim 5 further characterized in that the second named gear mechanism includes a spiral gear which is mounted concentrically in relation to the turntable and which rotates at a lower speed than that of the turn- 15 table.

8. The combination of claim 5 further characterized in that said first named gear mechanism includes a circular gear track and said second named gear mechanism includes a spiral gear 20 track one end of which merges into the circular gear track.

9. In a mechanism for rotating a sound recording or reproducing disk, the combination of a turntable, a constant-speed driving gear, a driven 25 gear having a circular gear track and a spiral gear track, selective means for meshing said driving gear in either of said gear tracks, and means including gearing whereby said driven gear effects rotation of said turntable.

30 10. In a gear transmission; the combination of a constant-speed driving gear; a driven gear provided with a circular gear track and a spiral gear track, said circular track being adapted to effect rotation of said driven gear at a constant 35 angular velocity and said spiral track being adapted to effect rotation of said driven gear at a variable angular velocity; and selective means for positioning said driving gear to mesh in either of said gear tracks.

40 11. In a gear transmission; the combination of a constant-speed driving gear; a driven gear provided with a circular gear track and a spiral gear track, said circular track being adapted to effect rotation of said driven gear at a constant angular velocity and said spiral track being adapted to effect rotation of said driven gear at a variable angular velocity; means for disengaging said driving gear from said gear tracks; and selective means for positioning said driving 50 gear to mesh in either of said gear tracks.

12. In a mechanism for rotating a sound recording or reproducing disk, the combination of a turntable, a spiral gear provided with a toothed track and connected by gearing to said turntable, 55 a constant-speed gear for driving said spiral gear, means for positioning said driving gear to engage said spiral gear, and means for positioning said spiral gear to engage said driving gear at a predetermined point in said track.

60 13. The combination of claim 12 further characterized in that the last named means has provision for being manually operated.

14. The combination of claim 12 further characterized in that the last named means has provision for being electrically operated.

65 15. In a mechanism for rotating a sound recording or reproducing disk, the combination of a housing, a turntable non-rotatably mounted on a shaft, a gear disk rotatably mounted on said shaft and provided with a spiral gear track on one face and gear teeth around its periphery, a constant-speed motor driving a shaft positioned radially of said gear disk and parallel to said face thereof, a pinion slidably and non-rotatably 70 75

mounted on said last named shaft and adapted to engage said spiral gear track, gear mechanism whereby said gear disk drives said first named shaft to rotate said turntable, means for maintaining said gear disk in alignment relative to said pinion, means for disengaging said pinion from said spiral gear track, and means for shifting said pinion radially of said gear disk.

5 16. The combination of claim 15 further characterized by the provision of means for rotating said gear disk independently of said turntable and said pinion.

10 17. The combination of claim 15 further characterized by the provision of means including said 15 pinion for rotating said gear disk independently of said turntable.

15 18. The combination of claim 15 further characterized in that said motor is energized by means of two electrical circuits, one of said circuits being controlled by a switch and the other being controlled by a slip-ring connected to said gear disk, said slip-ring being provided with two brushes and having an insulating inset so positioned as to contact with one of said brushes at a

predetermined point during the rotation of said slip-ring thereby breaking said second named circuit.

19. In a mechanism for rotating a sound recording or reproducing disk, the combination of a turntable, a constant-speed driving gear, a driven gear provided with a spiral gear track adapted to effect rotation of said driven gear at a uniformly increasing or decreasing angular velocity and further provided with a circular gear track adapted to effect rotation of said driven gear at a constant angular velocity, gear mechanism connecting said driven gear to said turntable and adapted to rotate said turntable at either of two predetermined constant angular velocities, and selective means for effecting rotation of said turntable at either of said predetermined constant angular velocities. 5 10 15

20. The combination of claim 19 further characterized in that said driven gear is provided with two circular gear tracks, thereby being adapted to effect rotation of said driven gear at either of two predetermined constant angular velocities. 20

CHESTER W. LARNER.
